UNITED STATES PATENT OFFICE.

LEWIS R. HEIM, OF DANBURY, CONNECTICUT, ASSIGNOR, BY MESNE ASSIGNMENTS, TO
CINCINNATI GRINDERS INCORPORATED, OF CINCINNATI, OHIO, A CORPORATION
OF OHIO.

GRINDING MACHINE.

Application filed October 8, 1921. Serial No. 506,222.

This invention relates to grinding apparatus, and more particularly to apparatus especially suited to grind cylindrical bodies, such as rolls and the like. One of the objects thereof is to provide a practical apparatus of the above nature characterized by efficient and accurate action. Another object is to provide apparatus of the above nature of simple and yet secure construction in which the parts are readily accessible. Another object is to provide apparatus of the above nature characterized by improved feed of the articles to be ground. Another object is to provide apparatus of the above nature which shall be readily adaptable to accommodate various sizes and shapes of material, and to meet varying conditions of practical use. Other objects will be in part obvious and in part pointed out hereinafter.

The invention accordingly consists in the features of construction, combinations of elements and arrangement of parts which will be exemplified in the structure hereinafter described and the scope of the application of which will be indicated in the following claims.

In the accompanying drawings in which is shown one of various possible embodiments of this invention,

Figure 1 is a plan view of the same;
Figure 2 is a front elevation; and
Figure 3 is an end elevation.

Similar reference characters refer to similar parts throughout the several views of the drawings.

Referring now to Figure 1 of the drawings, there is shown a frame 10 having mounted thereon a carriage 11 which is adjustable transversely of the frame as by means of the bolts 12 and slots 13 by which the carriage is held in position. Journaled on this carriage in suitable bearings 14 is a shaft provided with a pulley 15. At the inner end of this shaft is mounted by means of a suitable holder 16 a ring grinding wheel 17 of emery or like material.

At the opposite end of the frame 10 is a carriage 18 adjustable longitudinally of the machine by the usual threaded connection controlled by the feed wheel 19. Upon this carriage and journaled in the bearings 20 is a shaft having the pulley 21 fixed thereto. At the inner end of this shaft is a holder 22

for another ring wheel 23 of a construction 55 and composition similar to the wheel 17.

The pulleys 15 and 21 are respectively driven from the pulleys 24 and 25 upon a drive shaft 26 in the base of the machine. It is to be understood that the pulley 17 is 60 driven at such high speed as to give the peripheral travel of the wheel 17 a rate of several thousand feet per minute. It is also to be understood that the pulley 21 is driven at a much lower speed, perhaps in the general neighborhood of fifty R. P. M. or less, depending upon the diameter or size of the wheel 23, and so that the latter will perform the functions hereinafter noted.

By reference to Figure 1 of the drawings 70 it will be seen that the shafts are so positioned that the portions of the wheels between the axes of the shafts overlap one another in a radial direction. In other words, the wheels are offset transversely as well as 75 longitudinally, and in this embodiment are operative by way of their side faces.

The direction of drive of these wheels is such that the grinding wheel 17 at its point of action travels downwardly and the slow 80 or regulating wheel 23 travels in the opposite direction or upwardly where it contacts the work. The drive between the shaft 26 and the wheel shafts may be obtained by suitable belts 27 and 28 as indicated in the drawings; spring-pressed rolls 29 and 30 being utilized to maintain the desired belt pressure and increase the surface of contact between the belts and pulleys.

Intermediate the wheels is a work support 90 or carrier 31 on which the rolls rest while subjected to the action of the wheels in their travel up to and away from such point of action. This carrier is clamped as by a pivot bolt 32 within upright slots 33 in a 95 vertically extending supporting device 34. By this mounting it will be seen that an angular adjustment about the pivot bolts 32, as well as a vertical adjustment, permitted by slot 33, of the carrier or work support may 100 be secured. The vertically extending support 34 forms a portion of a small superposed lengthwise extending carriage 35 (see also Fig. 2) which is mounted by suitable ways on the carriage 18 so as to be adjustable with respect thereto by means of the threaded shaft 36 controlled by the small hand wheel 37. Also as the carriage 18 is

moved by the hand wheels 19, it moves the upper carriage 35 in like manner.

As best shown in Figure 1 of the drawings, there are provided guides at the entering side of the carrier 31 at 38 and 39 (see also Fig. 2). These guides are clamped against the sides of the carrier by the bolt 32 and project above its surface to form a trough, the guide 39 resting within the central recess formed by the grinding wheel 17 as is clearly shown in both Figures 1 and 2. These guides onto which the work is fed by any suitable means such as an inclined trough, receive the same and guide it right 10 up to the opposed surfaces of the wheels and also guide the rear end of each roll as it enters into the grip of the wheels. As the rolls pass out of the grip they are received between a short guide 40 and a long guide 15 41 clamped upon opposite sides of the carrier as by the screw 42. The extreme outer end of the guide 41 may be inclined slightly away from the wheel 23 in order to throw the rolls away from the downwardly moving portion of the wheel and into any suitable form of discharge chute. This guide 41 at its end toward the front of the machine rests within the central recess of the 20 annular regulating wheel 23 as is clearly 25 shown in Fig. 1.

The upper surface of the carrier as shown in Figure 3 of the drawings is in this embodiment substantially horizontal, and located above the plane of the axes of the two 30 wheels.

In the action of the apparatus, the rolls are fed as above described on to the carrier at the front side of the machine, that is, between the guides 38 and 39. From this 35 point they travel in the direction indicated by the arrow in Figure 1 of the drawings into the grip of the wheels. When they enter the grip, the regulating wheel on account of its slow speed controls their movement, its grip upon the work being much greater 40 than that of the rapidly moving grinding wheel which continually cuts itself clear. The upwardly moving operative surface of the regulating wheel accordingly rotates the 45 roll in the direction indicated thereon in Figure 2 of the drawings and it is held firmly against the carrier and ground by the rapid downwardly moving face of the grinding wheel. Furthermore the contacting 50 surface of the regulating wheel has a component lengthwise of the carrier in the direction toward the rear of the machine and accordingly there is a carefully governed and properly predetermined rate of 55 feed of the rolls along the carrier. It is to be noted moreover that the active face of the grinding wheel also has a component in the direction of feed of the rolls at its point of contact therewith, and thus has a 60 tendency to aid instead of oppose this feed-

ing action. The rolls thus travel along under the control of the regulating wheel and are subjected to the action of a grinding wheel which is driven at the speed best suited for most efficient grinding. The rate of 70 drive of the regulating wheel moreover is so predetermined that the rolls will be rotated during the grinding action at the speed best calculated to produce uniform and accurate results. Furthermore, the rate of 75 feed is readily varied to suit the character of work to be ground, and other factors, for if the inclination or elevation of the work support is changed, there will be a corresponding variation in the feed rate. This 80 variation moreover may be gained without disturbing the rate at which the wheels are driven.

When it is desired to change the diameter of work acted upon, the regulating wheel 85 may readily be varied in its distance from the grinding wheel, and it is to be understood that it is positively held in such changed position with no tendency to follow up any diminution of the diameter of the article during the grinding action. When this adjustment is made, the carrier may be readily moved to occupy a position midway between the active faces of the 90 wheels, and if necessary the distance between the guide plates may be varied by shims or otherwise. By the transverse adjustment of the grinding wheel, moreover, the amount of overlap of the two wheels 95 may be readily adjusted, and if desired larger or smaller wheels be employed by varying the distance between their axes. The operation of truing up the wheels may be accomplished in the usual manner by 100 running a double diamond along the path 105 of the work, and any wear or cutting away of the wheels may be compensated for by a suitable adjustment of the carriages 18 and 35.

It will thus be seen that all parts of the 110 machine are readily accessible and that it is readily adaptable to meet all conditions of work and use.

As various possible embodiments might be made of the above invention and as various changes might be made in the embodiment above set forth, it is to be understood that all matter hereinabove set forth or shown in the accompanying drawings is to be interpreted as illustrative and not in a 115 limiting sense.

I claim as my invention:—

1. In a grinding machine, in combination, 120 a grinding wheel having an annular operative surface, a regulating wheel having an annular operative surface, a frame mounting said two wheels with their axes of rotation substantially parallel and in a substantially horizontal plane but spaced laterally out of alignment and in such relation that said an-

- nular operative surfaces thereof overlap in a radial direction, means including a driven shaft rotatably mounted in said frame and extending in the general direction of the 5 axes of said wheels, said shaft having driving connections for driving said grinding wheel at a relatively high speed and for driving said regulating wheel at a relatively low speed, whereby said grinding wheel may 10 perform a grinding operation upon work interposed between said wheels and said regulating wheel may control the rotation of said interposed work, said shaft driving said two wheels in the same direction about their respective axes, whereby said overlapping portions 15 of the operative surfaces of said two wheels travel in opposite directions, means for moving one of said wheels substantially lengthwise of its axis of rotation to vary the distance between said overlapping portions 20 of the annular surfaces of the wheels, and a work support extending between said overlapping portions of the annular surfaces of said two wheels and adapted to support work 25 of round section in operative relation to said two wheels.
2. In a grinding machine, in combination, a frame rotatably supporting two substantially parallel shafts extending away from 30 one another and the one displaced laterally from the other, a grinding wheel having an annular operative surface mounted on the near end of one of said shafts, a regulating wheel having an annular operative surface 35 mounted on the near end of the other of said shafts, whereby the annular operative surfaces of said two wheels overlap in a radial direction, a work support for holding work of round section in operative relation to the overlapping portions of said two wheels, means for driving the said shafts in the same 40 direction about their axes so that the overlapping portions thereof travel in opposite directions and at respective speeds such that the grinding wheel may perform a grinding operation on the work and the regulating wheel control the rotation of the work during its action thereon by said grinding wheel, and a carriage movably mounted upon said slide and extending substantially alongside of the shaft carried by said slide for supporting said work support.
4. In a grinding machine, in combination, a grinding wheel having an annular operative surface, a regulating wheel having an annular operative surface, means mounting said two wheels with their axes of rotation substantially parallel and in a substantially horizontal plane but spaced laterally out of alignment and in such relation that said annular operative surfaces thereof overlap in a radial direction, means for driving said grinding wheel at a high speed of rotation about its axis, means for driving said regulating wheel at a much lower speed of rotation and in a direction about its axis the same as the direction in which said grinding wheel is driven about its axis, means for adjusting the position of one of said wheels substantially lengthwise of its axis of rotation to vary the distance between said overlapping portions of said annular surfaces of the wheels, means for adjusting the position of one of said wheels substantially transversely of its axis of rotation to vary the amount of said overlap, a substantially horizontal work support extending between said overlapping portions of said annular surfaces adapted to support work of general 50 cylindrical shape to be acted upon by both said grinding wheel and said regulating wheel, said work support projecting at each end beyond said annular surfaces of the wheels, and guides secured to the sides of each of said projecting ends of said projecting ends of said work support adapted to hold the work thereon away from contact with the central portions of the faces of said wheels interior of said annular operating faces thereof, said inner portions of the wheel faces being recessed to accommodate said guides.
3. In a grinding machine, in combination, a frame rotatably supporting two substantially parallel shafts extending away from one another and the one displaced laterally from the other, one of said shafts being carried by a slide mounted upon said frame for movement in a general direction in which 60
5. In a grinding machine, in combination, a grinding wheel having an annular operative surface, a regulating wheel having an 65

annular operative surface, means mounting said two wheels with their axes of rotation substantially parallel and in a substantially horizontal plane but spaced laterally out of alignment and in such relation that said annular operative surfaces thereof overlap in a radial direction, means for driving said grinding wheel at a high speed of rotation about its axis, means for driving said regulating wheel at a much lower speed of rotation and in a direction about its axis the same as the direction in which said grinding wheel is driven about its axis, means for adjusting the position of one of said wheels substantially lengthwise of its axis of rotation to vary the distance between said overlapping portions of said annular surfaces of the wheels, means for adjusting the position of one of said wheels substantially transversely of its axis of rotation to vary the

amount of said overlap, a substantially horizontal work support extending between said overlapping portions of said annular surfaces adapted to support work of general cylindrical shape to be acted upon by both said grinding wheel and said regulating wheel, means for adjusting the position of said work support in a direction substantially parallel to the axes of rotation of said wheels to center said work support in the space between said overlapping portions of the wheels, and means for adjustably tilting said work support for adjustably inclining the path of travel of the work thereon with respect to the operating surfaces of the wheels.

In testimony whereof, I have signed my name to this specification this 26th day of September, 1921.

LEWIS R. HEIM.
